(57) **CLAIM**

We claim the ornamental design for a double-recessed blister packaging, as shown and described.

DESCRIPTION

FIG. 1 is a perspective view of the double-recessed blister packaging viewed from the top;

FIG. 2 is a perspective view of the double-recessed blister packaging viewed from the top;

FIG. 3 is a top view of the double-recessed blister packaging;

FIG. 4 is a bottom view of the double-recessed blister packaging;

FIG. 5 is a side elevation view of the double-recessed blister packaging;

FIG. 6 is a side elevation view, opposite the side elevation view of FIG. 5 thereof;

FIG. 7 is another side elevation view of the double-recessed blister packaging;

FIG. 8 is another side elevation view, opposite the side elevation view of FIG. 7 thereof;

FIG. 9 is a cross-sectional view, taken in the direction of line 9-9 on FIG. 3; and,

FIG. 10 is a cross-sectional view, taken in the direction of line 10-10 on FIG. 3.

1 Claim, 5 Drawing Sheets
